Primary Examiner — Jennifer L Watkins*Assistant Examiner* — Samantha Lynne Brodowski(74) Attorney, Agent, or Firm — Hilary J. Sumner(57) CLAIM

The ornamental design for a turtle bag, as shown and described.

DESCRIPTION

FIG. 1 is front view of the turtle bag according to the design; FIG. 2 is a rear view thereof; FIG. 3 is a right side view thereof; FIG. 4 is a left side perspective view thereof; FIG. 5 is a top view thereof; and, FIG. 6 is a bottom view thereof.

The dash-dash lines on the surface of the turtle bag represent stitching and form a part of the claimed design.

The grey patterned surfaces in the drawings describe a contrasting appearance. The black shaded elements in the drawings represent a further contrasting appearance between the grey patterned surfaces and the non-patterned surfaces of the drawings.
